Primary Examiner — Daniel J Domino(74) *Attorney, Agent, or Firm* — Jordan IP Law, LLC(57) **CLAIM**

The ornamental design for a display screen with graphical user interface, as shown and described.

DESCRIPTION

FIG. 1 is a front view of a display screen with a user interface showing one embodiment of the new design.

FIG. 2 is another view of a display screen with a user interface showing another embodiment of the new design.

FIG. 3 is another view of a display screen with a user interface showing another embodiment of the new design.

FIG. 4 is another view of a display screen with a user interface showing another embodiment of the new design; and,

FIG. 5 is another view of a display screen with a user interface showing another embodiment of the new design. The broken lines showing an electronic device illustrate environmental subject matter, whereas the broken lines showing a display screen and elements of the graphical user interface illustrate portions of the article. No subject matter depicted in broken lines form part of the claimed design.
